UNITED STATES PATENT OFFICE.

GLENN L. GEER, OF ELMIRA, NEW YORK.

SHEET-MUSIC TURNER.

1,374,147.

Specification of Letters Patent. Patented Apr. 5, 1921.

Application filed June 18, 1919. Serial No. 305,013.

To all whom it may concern:

Be it known that I, GLENN L. GEER, a citizen of the United States of America, residing at Elmira, in the county of Chemung and State of New York, have invented certain new and useful Improvements in Sheet-Music Turners, of which the following is a specification.

The primary object of the invention is a provision of a device for easily turning sheet music and is especially serviceable for pianos and music racks whereby the musician may turn the music without assistance or any interruption to the playing, the music being firmly held in position for use and prevented from falling or slipping.

A further object of the invention is to provide a sheet music turner for instruments or racks combining cheapness with simplicity and being instantly operable for turning the music after the manner of a tripping operation.

A still further object of the invention is to provide means for turning the single sheet of a three-sheet piece of music easily and quickly, the device being simple in construction and inexpensive to manufacture while fully performing the object for which it is designed.

With these general objects in view the invention consists of the novel combination and arrangement of parts hereinafter fully described, illustrated in the accompanying drawings and then claimed. Like reference characters designate corresponding parts throughout the several views of the drawings and in which—

Figure 1 is a perspective view of the invention positioned for use upon a piano rail, a portion of the latter being shown and the music sheets being indicated by dotted lines.

Fig. 2 is a side elevation thereof partially broken away and with parts removed.

Fig. 3 is a sectional view of a portion of the invention upon an enlarged scale.

Figs. 4 and 5 are transverse sectional views taken upon lines IV—IV and V—V of Fig. 3 and

Fig. 6 is a detailed view showing the adjacent sheets of music with the holding arm in transverse sections.

Referring more in detail to my invention, I provide a support 10 preferably formed of sheet metal adapted for attachment to any desired member for conveniently positioning

the sheet music, the support 10 being herein illustrated provided with an angular attaching end 11 secured to the horizontal music rail 12 of the piano. In this manner, the support 10 preferably formed of slightly resilient sheet metal is adapted for positioning a double sheet of music 13 outstretched between the support 10 and the adjacent side 14 of the piano. The support 10 is inclined according to the slope of the piano 14 for pressing against the music 13, holding it in position upright on the rail 12 with the central or creased portion of the sheet 13 behind the support 10.

A tube 15 secured to the support 10 by strap 16 or any suitable manner has a shaft 17 axially journaled therethrough by means of caps 18 threaded in the opposite ends of the tube 15. An arm 19 projects perpendicularly from the upper end of the shaft 17, being rigidly secured to the shaft and having a plurality of clips 20 for securing the upper edge of a single sheet of music 21 to the arm 19. The clips 20 are preferably in the form of struck-up resilient portions of the arm 19 and suspend the sheet 21 from the arm exposing either side of the sheet 21 to view depending upon the position of the arm 19.

The shaft 17 is slidable longitudinally of the tube 15 through the caps 18 and is normally positioned depressed with the arm 19 seated in a hook or bracket 22 adjacent the top of the support 10 and whereby the arm 19 projects from one edge of the support 10 with one side of the sheet 21 viewable. A helical spring 23 encircles the shaft 17 within the tube 15 having one end of the spring secured as at 24 to the shaft 17 and the other end of the spring projecting through a side slot 25 of the stationary tube 15.

From this construction it will be understood that the bracket 22 normally maintains the arm 19 and sheet 21 outstretched at one side of the support 10 while upon elevating the shaft 17, the spring 23 will automatically swing the arm 19 and sheet 21 to the opposite side of the support 10, exposing the opposite side of the sheet 21 to view, the elevating of the shaft 17 releasing the arm 19 from the bracket 22.

An operating lever 26 is pivoted in ears 27 upon the end 11 of the support 10, the inner end of the said lever being in the form of a socket 28 in which the lower end of the shaft 17 is seated after the nature of a

thrust bearing, the spring 23 normally holding the shaft 17 lowered while the overbalanced outer end 29 of the lever 26 assists in maintaining the shaft 17 and lever 26 in 5 their operative engagement.

With the device positioned upon a piano or music rack and the sheet 21 as well as the sheet 13 of music positioned as illustrated, the player may instantly depress the finger 10 piece 30 at the outer extremity of the lever 26 thereby releasing the arm 19 and causing the spring 23 to automatically turn the sheet 21. While the preferred form of the invention, as herein set forth, fulfills the objects 15 designed for the same, minor changes may be made therein if found desirable without departing from the spirit and scope of my invention.

What I claim as new is—

- 20 1. A music leaf turner comprising a resilient sheet metal support having an angular lower end adapted to be secured to a music rail with the main portion of the support projecting upwardly adjacent the piano for the holding reception of a sheet of music therebetween, a tube upon the front of the support, a shaft slidable and rotatable through the tube, an arm projecting from the shaft adapted for supporting a sheet of

music, a bracket upon the support in which 30 the arm is normally seated, a helical spring within the tube encircling the shaft for revolving the latter for turning the music when the arm is released from the bracket, and an operating lever pivoted to the lower 35 end of the support having a socket at its inner end within which the shaft is seated and having a finger piece upon its outer end for shifting the lever to elevate the shaft and free the arm carried thereby from engagement with the bracket.

2. A music leaf turner of the type described comprising a mounting bracket, a tubular housing fixed to the bracket, a tensioned shaft rotatably and slidably mounted 45 in the tubular housing, a music leaf engaging arm carried by the upper end of the shaft, a lug carried by the mounting bracket normally engaging the music leaf arm for holding the shaft under tension and a lever 50 pivoted to the lower end of the mounting bracket with the lower end of the tensioned shaft seated on the inner end thereof whereby movement of the lever will elevate the shaft to free the music leaf carrying arm 55 from engagement with the retaining lug.

In testimony whereof I affix my signature.

GLENN L. GEER.
